SKATE

Edward Klevstad, Detroit, Mich.

Application January 27, 1937, Serial No. 122,636

10 Claims. (Cl. 208—167)

This invention relates to improvements in skates, and refers to the type of skates described in my United States Patent No. 1,789,182 issued on January 13th, 1931, wherein a one-piece blade 5 is mounted beneath heel and toe plates, and wherein the former is movable relative to the latter.

In my patent above referred to a spring was mounted both upon the toe plate and the shoe 10 thereon tending to move the heel plate and that portion of the shoe thereon downward towards the blade. While this movement is very desirable I find that the operation of the spring, and the consequent downward movement of the rear 15 portion of the shoe and the heel plate, is impeded by ice and snow packing between the spring and the shoe. Further, in that invention the guide projecting downward from the heel was either free to travel upon the upwardly 20 projecting slide extending from the blade checked only during its upward travel by the spring aforementioned, and accelerated in its downward movement by the said spring; or else the guide and slide could be held rigid by the insertion of 25 a pin through both these parts thereby holding the heel plate solid with the blade in the conventional manner.

The present invention aims to provide a skate of the type referred to wherein the spring is 30 housed within the sole of the shoe thereby protecting it from ice and snow.

Another object of the invention is to provide a skate wherein a resilient member is housed at least partly within the heel of the shoe to 35 cushion the downward movement of the heel plate and act against the spring housed within the shoe sole; and wherein adjusting means are provided upon the heel plate, for holding the latter immovable relative to the blade, for permitting only quite limited movement of the heel plate, or for permitting a full movement of the latter cushioned in each direction by one of the two aforesaid springs.

A further object of the invention is to provide 45 such a skate wherein the coacting guide and slide, which are arcuate, upon the heel plate and blade respectively, are mounted under the heel to provide as long a radius as possible from their 50 axis which lies substantially at the junction of the rear margin of the toe plate and the sole of the shoe thereon.

Having thus briefly and broadly stated some 55 of the major objects and advantages of the invention I will now proceed to describe some em-

bodiments thereof with the aid of the accompanying drawings, in which:

Figure 1 illustrates a longitudinal view of a 5 skate with a shoe secured thereon, partly in section.

Figure 2 is an enlarged side view partly in section showing a heel plate and the cooperating parts.

Figures 3 and 4 are sections on the lines 3—3 and 4—4 respectively of Figure 2.

Figure 5 is an enlarged perspective view of the 10 spring which is housed in the shoe sole.

Figure 6 is an enlarged view partly in section showing the heel plate raised some distance above the skate.

Figure 7 is an enlarged side view, partly in section, showing a modified form of heel plate, and

Figure 8 is a plan view thereof.

Figure 9 shows a further modification, and

Figure 10 is a section on the line 10—10 of 20 15 Figure 9.

Referring to Figures 1 to 6 of the drawings, 1 designates a blade upon which a fixed toe plate 2 is mounted as by supports 3 and 4. Formed integral with the blade 1 and projecting upwardly therefrom is a slide 5 which is of arcuate form, the center from which the arc is described extending transversely across the rear margin of the toe plate 2 at its junction with the sole 6 of a shoe 7 secured thereon.

Provided in the heel 8 of the shoe 7 is an opening 9 and a circular aperture 10. Mounted upon the underside of the heel 8 is a heel plate 11 having a depending arcuate guide 12 which extends down the front and both sides of the slide 35 5 which is movable therein in a substantially vertical path. The guide 12 also projects rearwardly of the slide 5 and its two sides are held in spaced relation as by a nut and bolt 13 and 40 14. Formed in the heel plate 11 is a downwardly directed pocket 15 which registers with the heel aperture 10. The base and inner side of the pocket is also vertically slotted to permit vertical movement therein of a downwardly stepped rear portion 5a of the slide 5.

Mounted in one side of the guide 12 is a pin 16 which engages a groove 17 formed in one face of the slide 5; the said groove extends substantially the full length of the slide for the pin to slide therein and permits the guide and heel plate 50 to lift as shown in Figure 6. Formed from the base of the slot or groove 17 through the slide 5 is an opening 18 the purpose of which is explained hereafter.

Mounted for lateral movement upon the heel 55

plate 11 and housed in the heel opening 9 is a locking pin 19 downwardly from which a knob or finger hold 20 projects through a slot 21 formed through the said heel plate. The locking pin has grooves 22 formed across its upper face at right angles to its axis, and is supported in a resilient clip or bearing 23, secured to the heel plate 11. The pin 19 is thus mounted for axial movement. Formed in this clip is a downward projection 24 to resiliently engage any one of the grooves 22 and hold the locking pin against accidental axial movement in any one of three transverse positions.

Referring to Figure 3, when the knob 20 is moved all the way to the right the pin 19 is clear of the groove 17 and does not in any way interfere with the movement of the slide 5 in the guide 12. When the knob 20 is in its central position, shown in Figure 3, the pin 19 is in engagement with the groove 17 thereby halting upward movement of the heel plate 11 when the pin 19 strikes the top of the groove 17. Thus a limited lift of the heel plate is permitted. When the knob 20 is moved to its left hand position the pin 19 extends into the opening 18. The latter is so located that when this occurs the guide 12 is in its bottom position and the lower front margin of the guide bears upon the top of the blade 1. The heel plate is then of course locked against movement relative to the blade. When the pin 19 is in its right hand position and entirely clear of the groove 17 downward movement of the slide in the guide is halted by contact of the pin 16 with the upper extremity of the said groove.

Tending to move the heel 8 and heel plate 11 downward towards the blade 1 is a spring 26 which is housed within the sole 6 of the shoe 7. This spring alone is shown in Figure 5 so that its tendency to press the heel and heel plate in the direction indicated is readily apparent. Acting against the spring 26 is a stronger helical spring 28 mounted partly within the heel aperture 10 and partly in the pocket 15. The upper extremity 45 of this helical spring bears against the inverted base of the aperture 10 and its lower extremity bears either upon the downwardly stepped rear portion 5a of the slide 5, or, when the heel plate is raised to a considerable extent above the blade 50 as shown in Figure 6, against the base of the pocket 15. This spring 28 tends to force the blade downward from the heel plate during its initial movement and also cushions the heel plate as it reaches its downward limit of travel towards the blade.

From the foregoing it is apparent that by adjusting the locking pin 19 the heel plate 11 may be locked relative to the blade, permitting limited vertical movement thereover, or permitting considerable vertical travel. Moreover by throwing the weight of the body largely on to the toe plate 2 the helical spring 28 more than counterbalances the spring 26 and assists the initial upward movement of the heel plate 11; the spring 28 also 65 cushions the said heel plate as it reaches its bottom limit of travel.

In the modification shown in Figures 7 and 8 the construction is identical with that previously described except that a leaf spring 28a is substituted for the spring 28. One extremity of this spring 28a is anchored in the heel 7a between layers of leather or other suitable material indicated at 7b and 7c. The free extremity of this spring 28a bears against the step 5a of the slide 75 and tends to force it down to the position indi-

cated at 5aa. In this instance the pocket 15 shown in Figures 1, 2 and 6 is dispensed with.

In the modification shown in Figures 9 and 10 the slide 5b is pivotally supported upon the blade 1 by a pin 1b. The purpose of this construction is to permit the slide to float somewhat in the guide and insure free movement of the former in the latter as they travel through their arcuate path.

While in the foregoing the preferred embodiments of the invention, which reside in a novel combination and arrangement of parts, have been described and shown, it is understood that the construction is susceptible to such further alterations and modifications as fall within the scope 15 of the appended claims.

What I claim is:

1. In a skate, the combination of a blade, a toe plate rigidly supported thereover, a slide extending upwardly from the blade, a heel plate, a guide 20 projecting downwardly from the heel plate, said slide being adapted to travel along a substantially vertical path in said guide, and a selective means permitting either a partial or a full movement of the slide in the guide. 25

2. In a skate, the combination of a blade, a toe plate rigidly supported thereover, a slide extending upwardly from the blade, said slide being integral with the blade, a heel plate, a guide projecting downwardly from the heel plate, said slide being 30 adapted to travel along a substantially vertical path in said guide, and a selective means permitting either a partial or a full movement of the slide in the guide.

3. In a skate, the combination of a blade, a toe 35 plate rigidly supported thereover, a slide extending upwardly from the blade and pivotally supported by the latter, a heel plate, a guide projecting downwardly from the heel plate in which the slide is adapted to move along a substantially 40 vertical path, and a selective means permitting either a partial or a full movement of the slide in the guide.

4. In a skate, the combination of a blade, a toe plate rigidly supported thereover, a slide extending 45 upwardly from the blade, a heel plate, a guide extending downwardly from the heel plate in which the slide is movable along a substantially vertical path, and a selective means for permitting either a partial or a full movement of the 50 slide in the guide or for locking the slide in the guide to maintain a constant spacing between the heel plate and the blade.

5. In a skate, the combination of a blade, a toe 55 plate rigidly supported thereover, a slide extending upwardly from the blade, a heel plate, a guide extending downwardly from the heel plate in which said slide is movable along a substantially vertical path, one face of the slide being provided with a groove therein and an aperture 60 extending from the base of the groove through the slide, a locking pin carried by the heel plate and mounted for transverse movement relative to the slide, said pin being adapted to engage said aperture and said groove, or said groove only, or to 65 be moved clear of the latter.

6. A skate comprising a blade, a toe plate rigidly supported thereover, said toe plate having the sole of a shoe secured thereon, a slide projecting upwardly from the blade, a heel plate, a guide extending downwardly from the heel plate in which said slide is movable along a substantially vertical path, said slide being downwardly stepped, and a spring housed at least partly in said shoe heel 70 adapted to bear upon the downwardly stepped 75

portion of the slide to force the blade farther from the heel plate.

7. A skate comprising a blade, a toe plate rigidly supported thereover, said toe plate having the sole 5 of a shoe secured thereon, a slide projecting upwardly from the blade, a heel plate, a guide extending downwardly from the heel plate in which said slide is movable along a substantially vertical path, said slide being downwardly stepped, a 10 helical spring housed at least partly within an opening formed in the shoe heel and adapted to bear against the downwardly stepped portion of the slide, and a downwardly directed pocket formed in the heel plate to receive the lower portion 15 of the helical spring.

8. A skate comprising a blade, a toe plate rigidly supported thereover, said toe plate having the sole of a shoe secured thereon, a slide projecting upwardly from the blade, a heel plate, a guide 20 extending downwardly from the heel plate in which said slide is movable along a substantially vertical path, said slide being downwardly stepped, and a leaf spring having one extremity mounted

upon the shoe heel in an aperture formed therein, said spring being adapted to bear upon the downwardly stepped portion of the slide to force the blade farther below the heel plate.

9. In a skate, the combination set forth in 5 claim 5, wherein a spring clip upon the heel plate supports the locking pin for axial movement, and coacting means on said clip and pin engage at three axial positions of the pin and hold the latter against accidental movement in the clip.

10. In a skate, the combination of a blade, a toe plate rigidly mounted thereover to support the front portion of a shoe, a slide extending upwardly from the blade, a heel plate to receive the heel of the shoe, a guide projecting downwardly from the heel plate, said slide being adapted to travel along a substantially vertical path in said guide, resilient means interposed between the shoe heel and the slide tending to move the latter downwardly in the guide, and a selective means permitting either a partial or a full movement of the slide in the guide. 15 20

EDWARD KLEVSTAD.
